UNITED STATES PATENT OFFICE.

HERMAN A. SPERLICH, OF HIGHLAND PARK, MICHIGAN.

WASHING-MACHINE.

1,276,984.

Specification of Letters Patent. Patented Aug. 27, 1918.

Original application filed March 30, 1917, Serial No. 158,607. Divided and this application filed March 21, 1918. Serial No. 223,733.

To all whom it may concern:

Be it known that I, HERMAN A. SPERLICH, a citizen of the United States, and residing at Highland Park, in the county of Wayne 5 and State of Michigan, have invented a new and Improved Washing-Machine, of which the following is a specification.

The present invention relates to a washing machine wherein the washing is accomplished in a cylinder that is mounted in a tub and arranged to rotate about a horizontal axis. It consists in certain means for detachably connecting the cylinder to its driving shaft and sealing the joint between 10 the driving shaft and the tub; also in a new and improved closure for the cylinder; also in certain other details of construction 15 shown, described and claimed.

This application is a division of my application on washing machines, Serial Number 158,607, filed March 30, 1917.

In the drawings, Figure 1 is a plan view showing a preferred embodiment of the invention, the closure for the cylinder being 20 removed. Fig. 2 is a section on the line 2—2 of Fig. 1. Fig. 3 is a fragmentary longitudinal central section of the inner drum showing the driving shaft and the sealing means. Fig. 4 is a fragmentary section on the line 4—4 of Fig. 3. Fig. 5 is a section on the line 5—5 of Fig. 1. Fig. 6 is a perspective view of the closure.

The tub which is supported on legs 1, 2, includes the trough-shaped body 4 and the 35 end walls 5. Mounted to rotate within the tub about a horizontal axis is a washing cylinder that preferably includes the metal body portion 15 and ends 16, one of the latter having projecting therefrom a spindle 18 which is supported in a bracket 19 on the inner face of the tub. The other end of the tub has riveted thereto a bracket 20 which is shaped to detachably receive a 40 tapered nut 21 rigid on the end of the cylinder driving shaft 22 that passes out through the end wall 5 of the tub. The driving shaft turns in the inwardly projecting boss 24 of a casing element 25, leakage between the shaft and boss being prevented by a 45 packing nut 26 (screwed onto the nut 21) and packing 28. The bracket 20 includes the outwardly projecting ribs 30 and 31 which are joined by the rib 32; it also in-

cludes a rib 33 that does not, however, project as far outwardly as do the other ribs; 55 and which has an inclined face 34. It will be noted that the ribs 30 and 31 stand at an angle of 60° to the ribs 32 and 33, and that the rib 33 is spaced from the rib 32 sufficiently to form a pocket in which the tapered nut is snugly received. When the cylinder is to be put into the tub it is lowered until the spindle 18 is received in its socket in the bracket 19, the cylinder being turned so that the inclined face 34 of the rib is 60 below the axis of said cylinder, whereupon, when further pressure is applied to the cylinder, the face 34 wedges the nut 21 outwardly against the resiliency of the end of the tub until said end snaps the nut inwardly to bring it into close engagement 65 with the walls of the pocket formed by the ribs. Power now being applied to the shaft, the cylinder is of course turned in the same direction. In detaching the cylinder, it is 70 only necessary to press the end of the tub outwardly until the rib 33 clears the nut after which the cylinder may be lifted out, as is obvious.

The cylinder preferably includes the 75 wooden paddles 36 (as shown, four in number), one end of each of which is shallow. The deep ends of one pair of the paddles alternate with the shallow ends of the other. The portion 15 of the cylinder is provided 80 with a longitudinal opening, along the edges of which a series of headed screws 38, together with a screw 39 having a wing nut 40, project. A closure 41 for the opening has the circumferentially extending reinforcing plates 42, the outer ends of which are slotted at one side as indicated at 43 to allow them to be slipped endwise beneath the heads of the screws. Upon tightening 85 up on the wing nut the closure is, of course, 90 clamped firmly in position.

The cylinder driving shaft 22 has its outer end loosely mounted in the hub of a bevel gear 67 that is, in turn, rotatable in a bearing 68 formed on the casing element 25. The 95 inner face of the hub of the gear 67 is provided with clutch jaws with which jaws 69 on a clutch member 70 engage when said clutch member is in one position. The latter is keyed on the shaft 22 and may be 100 shifted longitudinally thereof by a crank 105

71 which carries a roller 72 that projects into a circumferential groove 73 in the clutch member. A lever 74 affords means for manipulating the crank, and means (not shown) automatically holds the crank at either limit of movement.

The gear 67 is driven in any suitable way, for example, as shown in my previous application above identified.

16 The details of construction may be varied considerably without departing from the spirit of the invention, and I do not, therefore, wish to be limited except as indicated by the subjoined claims.

15 I claim:

1. In a device of the character described, a frame, a tub supported by said frame, a cylinder rotatable in said tub about a horizontal axis, a cylinder driving shaft co-axial 20 with said cylinder and projecting through the end wall of the tub, a nut on the inner end of said shaft, a bracket secured to the adjacent end of the cylinder, said bracket having therein a socket in which said nut is 25 detachably received, said socket having a plurality of walls conforming to corresponding faces of the nut and having one wall inclined to the axis of the cylinder and of less depth than others, whereby the cylinder may 30 be driven by said shaft or may be detached therefrom after slightly spreading the cylinder from the corresponding end of the tub.

2. In a device of the character described, a frame, a tub supported by said frame, a cylinder rotatable in said tub about a horizontal axis, a cylinder driving shaft co-axial 35 with said cylinder and projecting through the end wall of the tub, a nut on the inner end of said shaft, a bearing for said shaft, 40 said bearing being in sealed relation to the end of the tub, means for sealing the joint between the nut and the bearing, a bracket secured to the adjacent end of the cylinder, said bracket having therein a socket in 45 which said nut is detachably received, whereby the cylinder may be driven by said

shaft or may be detached therefrom and removed from the tub at will.

3. A washing cylinder comprising a perforated sheet metal cylindrical body and a 50 pair of ends for said body, a plurality of longitudinal wooden paddles in said cylinder, said body having an opening therein, headed members passing through the metal of the body from the outside and into the 55 paddles adjacent the opening, the heads of said members being spaced from the body, and a closure for said opening, said closure having slotted projecting portions adapted to be slid longitudinally of the cylinder 60 until they are received between the corresponding heads and the body, and means for retaining the closure in the last named position.

4. A washing machine comprising a tub, 65 a casing mounted on the outside of one end of the tub, said casing having a perforated boss projecting into the tub, a cylinder in the tub, a driving shaft for the cylinder projecting through the boss, a driving element 70 secured to the inner end of the shaft, said element constituting the support for the adjacent end of the cylinder and forming therewith a detachable driving connection, and a gland secured to the driving element 75 and preventing seepage of liquid in the tub into the bearing between the driving shaft and the boss.

5. A washing machine comprising a tub, 80 a casing mounted on the outside of the tub, 85 said casing having a bearing, a cylinder in the tub, a driving shaft in the bearing and projecting into the tub, a driving element secured to the inner end of the driving shaft, said element constituting the support and forming therewith a detachable driving connection, and a packing gland for closing the joint between the driving element and the casing and thereby preventing seepage of 90 liquid into the bearing.

HERMAN A. SPERLICH.
